UNITED STATES PATENT OFFICE.

CHARLES A. UPSON, OF LOCKPORT, NEW YORK, ASSIGNOR TO THE UPSON COMPANY, OF LOCKPORT, NEW YORK, A CORPORATION OF NEW YORK.

MACHINE FOR MAKING INSULATING BATS.

Application filed February 23, 1928. Serial No. 256,350.

My present invention relates to the manufacture of sound and heat resisting insulating material of the nature used for carpet linings and in building construction, the 5 same consisting in general of a soft fibrous interior body and liner sheets applied to one or both sides thereof, and the invention has for its object to provide a simple and efficient machine for rapidly making a product 10 of this nature in large quantities, and as a continuous process. The invention also contemplates the provision of means for rendering the material fire resisting.

To these and other ends the invention relates 15 in certain improvements and combinations of parts, all as will hereinafter be more fully described, the novel features being pointed out in the claims at the end of the specification.

20 In the drawings:

Fig. 1 is a side elevation of a machine constructed in accordance with and illustrating one embodiment of my invention;

Fig. 2 is a plan view partly broken away 25 of a preferred construction of the insulating product that the machine produces;

Fig. 3 is a transverse sectional view through the material shown in Fig. 2;

Fig. 4 is an enlarged longitudinal sectional view partially broken away through the central portion of the machine;

Fig. 5 is an enlarged elevation of the central portion of the machine;

Fig. 6 is an enlarged detail view partly broken away and partly in section of one of the feed roll couples and their driving gear;

Fig. 7 is an elevation of the driving end of a feed roll;

Fig. 8 is an elevation of the opposite end 40 of the couple, and

Fig. 9 is an enlarged section through the driving gear, taken on the line 9—9 of Fig. 5.

Similar reference numerals throughout the several views indicate the same parts.

45 The product or insulating material itself forms no part of the present invention, being fully described and claimed in a companion application filed by me concurrently herewith, but I will first briefly describe the general construction thereof in its preferred form.

Referring to Figs. 2 and 3, 1 indicates a central body of soft, heterogeneously arranged felted fibres, formed into a flat bat. 55 On opposite sides thereof are applied a plu-

rality of longitudinally extending parallel strips 2 and 3 of strong paper, or similar material. Corresponding units on opposite sides are arranged opposite each other in pairs, as shown in Fig. 3, and the strips 60 are secured to the bats by sewing them together, as indicated at 4. With respect to some or all of the interior strips 3 a double line of stitching is used as shown, and when the article is manufactured in great widths 65 as is contemplated by the present invention, it is cut along longitudinal lines, indicated at 23 running between these double stitches so that the severed pieces are strongly secured by at least one line of stitching at 70 both of their edges. This stitching holds the bat body firmly in place against creeping, or shifting. After the sewing paper liners 5 are applied to the opposite faces, and cemented thereto by the use of a suitable adhesive, such as a solution of sodium silicate, asphaltum, glue or other well known cements used in the paper making art. This adhesive body is indicated at 6 and has the effect not 75 only of securing the liner to the strips, but of imbedding the stitches 4 therein, so that the ends of each thread passing through the bat is firmly anchored between the liner and the strip.

Fig. 1 gives the general view of the making machine, and I will first give a general description with reference to that showing in which G indicates generally a Garnett picker, or familiar type of bat making machine, the details of which are of no consequence to this invention and application. It is sufficient to say that the flat fibrous bat 1 issues therefrom in a continuous strip between discharge rollers 7 onto a table 8. Next adjacent thereto are a pair of supports 9 carrying axles 10 upon which are supported above and below the table rolls 11 of strip paper suitably spaced to lay the strips 3 at the proper interval in a continuous manner upon the traveling bat. These elements together with the liners about to be described are drawn through the machine by means of a plurality of feed and pressure rolls 12 carried by a frame work 13, which rolls are suitably driven and may be heated or not 100 according to the adhesive and other material used.

As the bat with the strips thereon passes across the table 8 toward the feed roll, it travels through a multiple needle sewing 110

machine 14, which applies the stitching 4. After the sewing operation a lower liner strip 5 is drawn from a supply roll 15 over suitable guide rollers and through a dope box 16, where the adhesive is applied to the upper face thereof by a roll 17. From thence the liner passes up and through the feed rolls 12 and becomes attached and pressed firmly to the under side of the bat, and the 10 under strips 3 thereon.

In case it is desired to impregnate the bat or inner fabric body with a fire resisting or a water resisting material, I prefer to introduce this in a powdered form from a hopper 18 supported in the frame 13. Any suitable substance may be used, and it is sifted down upon the exposed surface of the bat from one of the feed rolls 12^a, which as shown cooperates with the mouth of the 20 hopper. During the further travel of the structure through the machine this powder is automatically shaken through to impregnate the interstices of the fibrous mass.

The upper liner 5^a is next applied to the 25 upper surface in the same manner as that described with respect to the lower liner. It is drawn from a supply roll 19 over suitable guides through an upper dope box 20, where the adhesive is applied by roller 21 30 to its under surface before it passes between the rolls 12. Beyond this point after passing through several more feed and pressure rolls the structure becomes a finished material. If the machine is a large one and it is 35 desired to cut the material longitudinally to divide it into more convenient widths I arrange upon the frame 13 a plurality of suitably driven upper and lower slitting knives 22. These are so arranged that they 40 engage and cut in between the double lines of stitching on the interior strips 3, as indicated at 23 in Fig. 2. This leaves the edges of the bat well supported on all sides.

From the feed rolls the finished material 45 is carried over an endless conveyer 24 to the desired point of delivery. In the present instance I have shown it delivered to a suitable swatching machine 25 which automatically folds the strips in zig-zag piles and 50 severs it into desired lengths, but the details of this are of no more concern to this invention than is the particular construction of the machine at the other end, which prepares and feeds the bat.

55 As shown in Fig. 4, the upper liner sheet 5^a passes around guide rolls 26, 27 and 28 in the dope box 20 and thence around the platen roll 29, which brings its under face in contact with the adhesive applying roll 21 running in the adhesive receptacle 30. Its dry side thence passes over guide roll 31 and downwardly to the feed roll. The dope box 20 is suitably heated or the rolls therein 60 are heated in case an adhesive is used of a 65 nature requiring heat to maintain it liquefied.

The under liner 5 similarly passes over guide rolls 32, 33 and 34 in the order named, the last mentioned two being in the dope box 16. Its upper side receives the adhesive from roll 17 running in the adhesive receptacle 35 as it passes around the opposed roll 36 and thence to the feed roll.

The feed rolls 12 are preferably hollow and as before stated, may be steam heated for which purpose the stub axles 37 (Fig. 75 6) upon which they turn in bearing blocks 38 and 39 carrying ball bearings 40 terminate in threaded nipples 41 for the steam pipe connections at both ends, the lower bearings 39 are adjustable in the bearing frame 42 by means of individual jack screws 43. The upper bearings 38 are floating bearings thrust downwardly for yielding contact of the upper roll with the lower roll, by means of springs 44, having adjusting 85 screws 45. Both bearings are provided with gib 46 running on ways 47 on the frame 42 as shown in Fig. 8. At one end the stub shafts 37 are provided with intermeshing gears 48 and 49 splined thereon, whereby 90 the upper roll is driven by the lower roll in an opposite direction, through a gear chain best shown in Figs. 5 and 9, and about to be described.

The central power drive shaft 50 is centrally arranged on the frame 13 with respect to the feed rolls and its motion is distributed to the latter in both directions. It has bearings 51 and 52 in a suitable gear box 53, and is turned by a sprocket 54 connected to a suitable source of power, not shown. A pinion 55 on this shaft 50 meshing with the gear 56 on a shaft 57 and through a pinion 58 on the latter drives a central gear 58^a on a stub shaft 59 on the inner wall of the gear box. This central gear 58^a is in mesh with the lower feed roll gears 48 on each side of it and they in turn drive each other along the line of feed rolls through intermediate transmission gears 59. Sprocket connections 60, 61 and 62 from certain of the feed roll gears respectively drive the two adhesive rolls 17 and 21 and a drive roll 63 for the conveyer 24.

I claim:

1. In a machine for making insulating material as a continuous operation, the combination with means for feeding and conveying a felted bat of loosely associated heterogeneous fibres along a fixed path of travel, means for supplying continuous strips of thin flexible material to a surface of the bat and to said feeding and conveying means to lay the strip in parallel relationship longitudinally of the bat during travel, a sewing machine arranged to stitch the said strips to the bat, means beyond the sewing machine in the path of travel for supplying a continuous liner sheet of thin flexible material to the feeding and conveying means to lay

the same upon the strips and an adhesive applying device cooperating with one of said last mentioned elements to cement the liner to the strips and the ends of the stitches in place between them.

2. In a machine for making insulating material as a continuous operation, the combination with means for feeding and conveying a felted bat of loosely associated heterogeneous fibres along a fixed path of travel, means for supplying continuous strips of thin flexible material to a surface of the bat and to said feeding and conveying means to lay the strip in parallel relationship longitudinally of the bat during travel, a sewing machine arranged to stitch the said strips to the bat and to apply double lines of stitching on selected strips, means beyond the sewing machine in the path of travel for supplying a continuous liner sheet of thin flexible material to the feeding and conveying means to lay the same upon the strips, an adhesive applying device cooperating with one of said last mentioned elements to cement the liner to the strips and the ends of the stitches in place between them and slitting knives arranged in alignment with the strip reels to cut the material into a plurality of strips along lines lying between the double rows of stitching on selected strips.
3. In a machine for making insulating material as a continuous operation, the combination with means for feeding and conveying a felted bat of loosely associated heterogeneous fibres along a fixed path of travel, means for supplying continuous strips of thin flexible material to a surface of the bat and to said feeding and conveying means to lay the strip in parallel relationship longitudinally of the bat during travel, a sewing machine arranged to stitch the said strips to the bat, means beyond the sewing machine in the path of travel for supplying a continuous liner sheet of thin flexible material to the feeding and conveying means to lay the same upon the strips, and means located in advance of the liner supplying means for sifting a proofing material upon the bat before it is covered.

CHARLES A. UPSON.
